UNITED STATES PATENT OFFICE.

WILLIAM REDFORD MULOCK, OF WINNIPEG, MANITOBA, CANADA.

DEVICE FOR FEEDING STRAW FUEL TO STOVES.

1,174,088.

Specification of Letters Patent.

Patented Mar. 7, 1916.

Application filed April 27, 1915. Serial No. 24,280.

To all whom it may concern:

Be it known that I, WILLIAM REDFORD MULOCK, of the city of Winnipeg, in the Province of Manitoba, Canada, have invented 5 certain new and useful Improvements in Devices for Feeding Straw Fuel to Stoves, of which the following is the specification.

The invention relates to improvements in devices for feeding straw fuel to stoves and 10 the principal object of the invention is to provide a handy household appliance which can be readily installed in a room and will automatically and intermittently feed the straw fuel, placed therein, to the stove to 15 which it is connected and thereby allow the farmer to utilize his own straw for heating purposes and to advantage.

A further object of the invention is to construct an appliance of this kind which 20 can be readily set up and which has the parts constructed so that they will not readily get out of order and further, to construct the appliance in a durable manner, but yet inexpensive and efficient.

With the above and other objects in view, 25 which will become more apparent as the description proceeds, the invention consists essentially in the arrangement and construction of parts hereinafter more particularly 30 described and later pointed out in the appended claims, reference being had to the accompanying drawing, in which;

Figure 1 represents an end view of the device as it appears when installed. Fig. 35 2 is an enlarged detailed end view of the device. Fig. 3 is an enlarged detailed vertical sectional view of the device. Fig. 4 is a longitudinal sectional view through the appliance.

40 In the drawing like characters of reference indicate corresponding parts in each figure.

At the outset I wish to explain that the present practice, wherein straw is used as 45 a fuel, is to place the whole or uncut straw in a stove designed specially for the purpose and burn it. I have found that this is more or less impractical in so far as heating is concerned, for the reason that the straw, through becoming packed, smudges rather than burns with the result that the stove is inefficient as a heating proposition.

Further, if sufficient draft is provided in a stove of this kind, the straw burns too quickly and needs replenishing too often. 55

My invention relates not particularly to a specially constructed stove, but to a device for feeding cut straw to the stove automatically and intermittently. By having the straw cut into short lengths and by providing a device to feed it, as above stated, the straw burns properly for effective heating purposes and continual attention is not required. In the specification I have shown and described a special device for this feeding purpose, but it will be understood that this can be readily modified without departing from the spirit of the invention. 60 65

Referring now to the drawing; 1 represents a stove of any suitable form suitably interlined with fire bricks 2 and presenting a grate 3.

4 is the top of the stove, 5 the ash door and 6 is the flue. To this stove I feed straw which has been previously cut by a suitable 75 machine into short lengths, say possibly a half an inch long.

The device for feeding the straw to the stove is now described; 7 represents a receptacle or container for the cut straw indicated by the reference letter 8. This container has a closed top and has the bottom thereof hopper shaped as indicated at 9 and terminating in an outlet neck 10. The ends of the hopper are supplied with handles 11 80 and 11' so that the same can be carried about 85 for refilling and resetting purposes.

12 is a cylindrical drum having one end permanently closed as shown at 13 and the other end open as shown at 14, and fitted with a closure cap 15. This cap can be fastened to the drum end by removable bolts 16 so that it can be readily taken off. The drum is provided at the top and bottom sides with elongated inlet and discharge openings 17 95 and 18, these openings being bounded respectively, by outstanding surrounding flanges 19 and 20. The flange 19 is designed to receive and support the neck 17 of the straw container 7 so that the straw can feed from the container through the opening into the drum. The flange 20 is designed to feed into a feed pipe 21 leading to the top of the stove and opening to the interior of the 100

stove through a flanged collar 22 resting on the stove top. The drum is suspended in an elevated position, adjacent the stove, by brackets 23 and 24 permanently fastened to 5 an adjacent support such as a wall 25. Within the drum I have rotatably mounted a cylindrical distributor 26 having a plurality of feed receiving, longitudinally disposed pockets 27 therein, the pockets being 10 equally spaced around the circumference of the distributor. End spindles 28 and 29 extend from the distributor, and are mounted in suitable bearings provided in the end 13 of the casing and in the cap 15. The outstanding end of the spindle 28 is squared as 15 shown at 28' to receive a hand tool such as a wrench.

30 is a spool mounted on the spindle 29 and fastened to the same by a removable 20 split pin 31. On the spool I have wound a cable, wire, rope or such like 32 having one end fastened to the spool and the other end extending and provided with a weight 33.

34 is a brake-shoe slidably fastened to the 25 cap 15 by pins 35 and such shoe is positioned so that it can be tightened by means of an adjusting screw 36 against the adjoining end of the spool. In this way I am 30 able to adjust the turning action of the spool and consequently the distributor, under the action of the weight, by tightening or loosening the shoe as the case may be.

Within the upper portion of the stove I 35 suspend a more or less cone shaped deflector 37 having perforations therein 38. The apex of the cone is centered below the entrance end of the pipe 21, so that the straw falling from the pipe strikes the deflector and is accurately spread in the stove by the 40 deflector. It is obvious that as the straw rolls over the deflector it will be liberated through the perforations 38 and consequently distributed more or less evenly over the grate 3.

45 When the device is installed, it is set by applying the hand tool to the squared end 28' and turning the distributor in a direction such that the cord is wound on the spool and the weight accordingly raised. The 50 distributor can then be locked in this position by tightening up the screw 36. The container 7 can then be removed and carried out and filled with cut straw in an out-building. It is then replaced on the distributor and the device is ready for use. The 55 rate at which the weight drops can be directly controlled by adjusting the shoe frictionally against the spool end. With this device, I propose keeping a fire in a 60 stove for over night without attention. This is simply a matter of designing the container with proper straw capacity and then adjusting the shoe so that the weight will fall once during the night. Obviously,

as the distributor turns slowly, under the 65 action of the weight, the straw is fed into the pockets and caught at the upper side and then turned around and released to the feed pipe 21 at the under side. The filling, as well as the releasing of this straw 70 from the pockets is distributed over a period of time, that is, the pockets are not filled or emptied abruptly. The advantage gained by this is effective on the feeding side of the distributor, as the straw is gradually released from the pocket to the pipe 75 with the result that it falls down the pipe 21 in a gradual stream and not in bulk, so to speak. This effects an even feed in the stove. It is of course, necessary to regulate the distributor so that the second pocket will not empty itself until the straw, admitted to the stove by the preceding pocket, is more or less well burnt. In this way the 80 fire is not "blanketed" in the stove and the 85 stove is accordingly effective as a heater.

From the construction of the device herein described, it will be seen that all the parts can be readily dismounted for cleaning or repair purposes. The distributor pulls out 90 of the drum when the closure cap has been undone. If desired, both the closure cap and spool can be removed from the spindle 29 by withdrawing the split pin 31.

What I claim as my invention is:— 95

1. A device for feeding straw fuel to stoves comprising, a suitably mounted, horizontally disposed, elevated, cylindrical drum having vertically opposing, diametrically opposite, full length inlet and discharge openings therein, a distributor rotatably mounted within the drum and having substantially U-shaped straw receiving pockets located therein and passing full length thereof and designed, in the rotation 105 of the distributor, to register successively with the inlet and discharge openings aforesaid, gravity operated means for continuously and slowly rotating the distributor, a removable straw container mounted on the 110 drum and designed to feed straw freely, by gravity, to the distributor and a gravity feed pipe having the upper end enlarged and communicating with the discharge opening and the lower end delivering to the stove. 115

2. A device for feeding straw fuel to stoves comprising, a suitably mounted, horizontally disposed, elevated cylindrical drum having vertically opposing, diametrically opposite, full length inlet and discharge 120 openings therein, a distributor rotatably mounted within the drum and having diametrically opposing pairs of substantially U-shaped straw receiving pockets located 125 therein and passing full length thereof and designed, in the rotation of the distributor, to register successively with the inlet and discharge openings aforesaid, gravity oper-

ated means for continuously and slowly rotating the distributor, a flat topped, hopper shaped bottomed straw container removably mounted on the drum and designed to feed straw contained therein freely, by gravity, to the distributor and a gravity feed pipe having the upper end enlarged and communicating with the discharge opening of the

drum and the lower end delivering to the stove.

Signed at Winnipeg, this 15th day of April, 1915.

WILLIAM REDFORD MULOCK.
